The ornamental design for a combination bottle and stopper, as shown and described.

DESCRIPTION

FIG. 1 is a perspective view of a design for a combination bottle and stopper, showing my new design.

FIG. 2 is a perspective view of the combination bottle and stopper of FIG. 1.

FIG. 3 is a right elevational view of the combination bottle and stopper of FIG. 1.

FIG. 4 is a left elevational view of the combination bottle and stopper of FIG. 1.

FIG. 5 is a front elevational view of the combination bottle and stopper of FIG. 1.

FIG. 6 is a rear elevational view of the combination bottle and stopper of FIG. 1.

FIG. 7 is a top elevational view of the combination bottle and stopper of FIG. 1.

FIG. 8 is a bottom elevational view of the combination bottle and stopper of FIG. 1.

FIG. 9 is a front elevational view of the stopper of FIG. 1, shown broken away for ease of illustration; and,

FIG. 10 is a front elevational view of the bottle of FIG. 1, shown broken away for ease of illustration.

The broken lines in the drawings illustrate a portion of the combination bottle and stopper which form no part of the claimed design.
